US00D588159S

(12) **United States Design Patent**
Griffin et al.

(10) **Patent No.:** **US D588,159 S**
(45) **Date of Patent:** **** Mar. 10, 2009**

(54) **COMBINED PUMP HOUSING AND PUMP CAP**

(75) Inventors: **Ronald H. Griffin**, Boonville, NC (US); **John Griffin**, Phoenix, AZ (US); **Gary Ortiz**, Clemmons, NC (US); **Joel Bowman**, Winston Salem, NC (US); **Dwayne Clark**, Summerfield, NC (US); **Jeffrey Pecca**, Hillsborough, NJ (US)

(73) Assignee: **Hayward Industries, Inc.**, Elizabeth, NJ (US)

(**) Term: **14 Years**

(21) Appl. No.: **29/267,940**

(22) Filed: **Oct. 25, 2006**

Related U.S. Application Data

(63) Continuation-in-part of application No. 29/253,402, filed on Feb. 6, 2006, now Pat. No. Des. 551,256.

(57) **CLAIM**

The ornamental design for a combined pump housing and pump cap, as shown and described.

DESCRIPTION

FIG. 1 is a left side perspective view of a combined pump housing and pump cap showing my new design;

FIG. 2 is a right perspective view;

FIG. 3 is a left elevational view;

FIG. 4 is a right elevational view;

FIG. 5 is a top plan view;

FIG. 6 is a bottom plan view;

FIG. 7 is a front elevational view;

FIG. 8 is a rear elevational view; and,

FIG. 9 is a left perspective view of the pump cap, it being understood that the body of the pump has been removed for ease of illustration.

The broken lines shown in the figures are for illustrative purposes only, and form no part of the claimed design.
